Des. 220,954
Patented June 22, 1971

220,954

MOBILE LOUNGE CHAIR

Jack E. Spence, Collins, Miss., assignor to Dura-Fold
Machine Works, Incorporated, Jackson, Miss.

Filed Jan. 22, 1970, Ser. No. 21,026

Term of patent 14 years

Int. Cl. D6—01

U.S. Cl. D15—11

FIG. 1

FIG. 2

FIG. 3

FIG. 4

FIG. 5

FIG. 1 is a side elevational view of a mobile lounge chair embodying my new design, with the side opposite being a mirror image of that shown;

FIG. 2 is a top plan view thereof;

FIG. 3 is an elevational view looking from the left of FIG. 1;

FIG. 4 is an elevational view looking from the right of FIG. 1; and

FIG. 5 is a bottom plan view of FIG. 1.

I claim:

The ornamental design for a mobile lounge chair, as shown and described.
